UNITED STATES PATENT OFFICE.

LEROY O. ARRINGDALE, OF BOSTON, MASSACHUSETTS, ASSIGNOR TO EDSON MANUFACTURING CORPORATION, OF BOSTON, MASSACHUSETTS, A CORPORATION OF MASSACHUSETTS.

PUMPING APPARATUS.

Application filed January 10, 1924. Serial No. 685,463.

To all whom it may concern:

Be it known that I, LEROY O. ARRINGDALE, a citizen of the United States, residing at Boston, in the county of Suffolk and State 5 of Massachusetts, have invented certain new and useful Improvements in Pumping Apparatus; and I do hereby declare the following to be a full, clear, and exact description of the invention, such as will enable others 10 skilled in the art to which it appertains to make and use the same.

The present invention relates to liquid pumping apparatus and more particularly to the reinforced flexible diaphragms employed in connection with such apparatus.

A well known type of hydraulic pump employs a flexible diaphragm in the general form of an annular ring which is clamped at its outer periphery to the stationary pump 20 casing and at its inner periphery to the movable pumping head. The movement of the pumping head to opposite limits of its stroke imparts a like movement to the inner periphery of the diaphragm, causing the latter to 25 move through and beyond the plane of the outer periphery to opposite sides. In the usual practice, the relatively heavy and stiff reinforced diaphragm is molded so that the inner periphery of the diaphragm is normally positioned below the outer periphery 30 corresponding to the lowermost position of the pumping head. Although this form of diaphragm has been developed as the result of long experience, nevertheless the effective 35 working life is relatively short and the diaphragms soon fail.

It is the object of the present invention to provide an improved and relatively simple form of diaphragm which shall have a 40 materially longer service period than diaphragms heretofore constructed.

With this object in view, the various features of the invention consist in certain novel features of construction, combinations and 45 arrangements of parts hereinafter described and claimed, the advantages of which will be obvious to those skilled in the art from the following description.

In the accompanying drawings illustrating 50 the preferred form of the invention, Fig. 1 represents a section in elevation of a conventional form of pump with the new diaphragm embodied therein; Fig. 2 is a detail

illustrating a diaphragm embodying the present improvements partly in section; and 55 Fig. 3 is a detail illustrating partly in section the conventional form of diaphragm now in use.

As will be evident to those skilled in the art, the hydraulic pump shown in the illustrated embodiment of the invention comprises generally a hollow base member 10 having an intake connection 12 and a grooved face 14 for supporting the outer periphery of the diaphragm. The diaphragm indicated generally at 16 is clamped to the face 14 through an upper clamping member 18, the two members serving to rigidly clamp the outer periphery of the diaphragm and seal the space enclosed by the base member 70 10. The inner periphery of the diaphragm is connected to a movable pumping head having a lower portion 20 and a cooperating upper portion 22 which serve to clamp the inner portion of the diaphragm between 75 them. A raised rib 24 formed upon the inner portion of the diaphragm cooperates with a pivoted valve member 26 to permit discharge of water from the suction chamber upon the down stroke of the pumping head. 80

It will be evident from an inspection of Fig. 1 that the pumping head carrying the inner periphery of the diaphragm moves from the lowermost position in which the diaphragm is shown in dot and dash lines 85 to the uppermost position indicated in a corresponding manner by dot and dash lines. In the lowermost and uppermost positions, the pumping head carrying the inner periphery of the diaphragm is farthest removed from the outer edge of the diaphragm so that the diaphragm must be constructed with sufficient material to permit movement into the upper and lower positions of the head. In the conventional form 90

of diaphragm shown at 30 in Fig. 3 the diaphragm is molded into a shape which corresponds with the lowermost position of the pumping head so that at one limit of movement of the pumping head there is no distortion or flexure of the diaphragm. Upon movement of the pumping head from the lowermost to the uppermost position, the diaphragm is made to assume approximately 100 the shape shown in dot and dash lines in 105 Fig. 3. During the movement of the dia-

phragm between these two positions, however, and especially when passing through the mid position, corresponding to the plane of the outer periphery of the diaphragm, 5 the diaphragm is severely distorted, due in part to the necessity of moving the diaphragm through the relatively limited space at different points between the inner and outer peripheries. In other words, the 10 movement of the inner periphery of the diaphragm toward the outer periphery as the mid position is approached compels a buckling or folding of the diaphragm, which puts a severe strain upon the material, especially as this folding is a material distortion 15 from the normal molded shape of the diaphragm.

According to the present invention, the diaphragm is molded in the mid position 20 with an annular depending fold of sufficient depth to provide the necessary material for the distention of the diaphragm during the movement of the pumping head to its outermost limits. With this form of construction, 25 the diaphragm when passing through the mid position, which normally represents the point of greatest distortion, is free from distortion and is subjected to only a gradual and comparatively easy flexure during its 30 movement in either direction from the mid position. As indicated in Fig. 1, the diaphragm is provided with an annular depending fold 32 positioned intermediate between the inner and outer peripheries of the 35 diaphragm and lying between the opposite surfaces of the base member 10 and the movable pumping head, as clearly indicated in Fig. 1. As the pumping head is moved from the mid position in either direction, the 40 fold is gradually flattened to distend the diaphragm and provide sufficient material for the desired movement of the pumping head. The location of the expansion fold intermediate the inner and outer peripheries of the 45 diaphragm leaves substantially flat peripheral portions adjacent the movable and stationary portions of the pump, which are subjected to a minimum of movement and flexure. 50 The diaphragms ordinarily employed for this purpose are made of molded rubber, or

rubber composition, and are ordinarily provided with an inner reinforcement of one or more layers of fabric. As these diaphragms in addition average a foot or more 55 in outer diameter and exceed a quarter of an inch in thickness it will be quite evident that the severe buckling to which the usual shape is subjected in order to permit its passage through the restricted space in mid position causes rapid deterioration of the diaphragm, even when made of a high quality 60 of rubber or rubber compound and strongly reinforced. The form of diaphragm illustrated and described, due to the more gradual change of shape and freedom from severe distortion, represents a very material 65 advance from the standpoint of increased life and serviceability.

While it is preferred to employ the specific construction and arrangement of parts shown and described, it will be understood that this construction and arrangement is not essential except so far as specified in the claim and may be changed or modified without departing from the broader features of 75 the invention.

The invention having been described, what is claimed is:

Pumping apparatus comprising a stationary pump housing, an annular diaphragm of rubber clamped at its outer periphery to the housing and molded with its inner and outer peripheries in substantially the same plane and with an annular depending fold 80 intermediate the inner and outer peripheries, a pumping head occupying the major portion of the space within the housing and clamped to the inner periphery of the annular diaphragm, the pumping head being 85 movable within the housing through the plane of the diaphragm and to opposite sides thereof, the annular depending fold of the diaphragm lying in the region of clearance 90 between the housing and head when the latter is passing through the plane of the diaphragm and the fold providing sufficient material to permit movement of the inner periphery to the opposite limits of movement 95 of the head.

LEROY O. ARRINGDALE.
